DESIGN FOR AN AUTOMOBILE EMBLEM PLATE OR SIMILAR ARTICLE

Bert A. Jamison, Arlington, Calif.

Application April 25, 1941, Serial No. 100,624

Term of patent 3½ years

To all whom it may concern:

Be it known that I, Bert A. Jamison, a citizen of the United States, residing at Arlington, in the county of Riverside and State of California, have invented a new, original, and ornamental Design for an Automobile Emblem Plate or Similar Article, of which the following is a specification, reference being had to the accompanying drawing, forming part thereof.

The single figure in the drawing is a perspective view of an automobile emblem plate showing my new design.

The drawing is shaded for color.

The characteristic features of the emblem plate of my design are indicated in full lines in the drawing.

I claim:

The ornamental design for an automobile emblem plate or similar article, as shown and described.

BERT A. JAMISON.
